WILLIAM C. FISHER, OF CHARLESTOWN, MASSACHUSETTS.

Letters Patent No. 88,152, dated March 23, 1869.

IMPROVEMENT IN SHUTTER-FASTENING.

The Schedule referred to in these Letters Patent and making part of the same.

To all whom it may concern:

Be it known that I, WILLIAM C. FISHER, of Charlestown, in the county of Middlesex, and State of Massachusetts, have invented certain Improvements in Fasteners for Shutters, &c., of which the following is a full, clear, and exact description, reference being had to the accompanying drawings, making part of this specification, in which—

Figure 1 is a vertical section, representing a shutter, secured in front of a window-sash by my improved fastening.

Figures 2 and 3 are perspective views of my fastening in detail.

Figure 4, modification to be referred to.

My invention has for its object to provide a reliable means of securing window-shutters in place, and liberating them, (irrespective of their thickness,) in a simple and expeditious manner; and

My invention consists in a bolt, provided with two or more notches, or with two or more holes, in connection with a weighted pawl, or other suitable catch, the bolt passing through the shutter and window-sash, or parts adjacent thereto, and extending sufficiently into the building to allow a weighted pawl, or other device, to engage with one of its notches, or holes, thus effectually locking the bolt, so as to render it impossible to remove the shutter, the said catch being instantly disengaged from its notch, or hole by a person within the building, when it is desired to remove the shutter from its position in front of the window, the said bolt being of a sufficient length to allow its inner end to extend through a shutter and sash, whether of greater or less thickness, in contradistinction to a bolt which will only answer for the particular shutter and sash for which it was fitted.

To enable others skilled in the art to understand and use my invention, I will proceed to describe the manner in which I have carried it out.

In the said drawings—

A is a window-frame,

B, the sash, and

C, the shutter of a window of a store or other building.

Through the shutter, and near its lower edge, is bored a circular hole, *a*, through which, and a similar hole, *b*, in line therewith, in the lower portion *c* of the sash, passes a bolt, *D*, the head *d* of which fits snugly into a recess formed in a metal plate, *E*, screwed to the outside of the shutter, the inner end of the bolt passing through an opening, *f*, in a metal plate, *G*, screwed to the inside of the lower cross-bar of the sash.

The inner end of the bolt is provided with a series of notches, *c*, the length of the bolt being sufficient to allow its notched portion to extend far enough beyond the interior of the lower cross-bar of the sash to enable the edge of a weighted pawl, *H*, to fall therein, the said pawl being pivoted, at *g*, to the metal plate *G*, just above the line where the notched end of the bolt *D* passes through.

In close proximity to the edge of the pawl is formed an enlargement, *h*, of a cylindrical shape, by which con-

struction the weight of the enlargement will always insure the descent of the edge of the pawl, and cause it to engage with one of the notches, *c*, when the bolt extends through to the interior.

When the shutter is to be removed, it is simply necessary for the operator to place his finger under the enlargement *h*, and raise it sufficiently to disengage the edge of the pawl from the notch, as seen in red, fig. 1, when the bolt may be pressed outwardly, and on being removed, the operator presses his hand upward on a projecting plate, *i*, to lift the shutter from the window-sill, on which it rests, immediately after which the shutter is inclined outwardly and drawn down, so as to allow its upper edge to pass the projecting cleats *k*.

It is evident that by making the bolt *D* long enough, and providing it with a number of notches, *c*, it may be used for securing shutters, whatever be the thickness of the shutter or sash through which it passes.

In fig. 4 is represented a circular bolt, provided with a series of notches, or grooves, extending around it. When such a formed bolt is employed, it is advisable to make the lower edge of the pawl of a concave semi-circular form, in order that it may have a more extended bearing and holding-surface in contact with the bolt.

My improved fastening is exceedingly simple and reliable, the operator only being required to press the notched end past the pawl, thereby raising it sufficiently until the required notch *c* comes under its edge, when it drops therein, and the bolt and shutter are securely locked in place.

Instead of a weighted pawl, a latch, sliding plate, or other suitable catch, may be used to engage with the notches in the bolt, and the latter may be provided with holes, instead of notches, and a catch especially adapted therefor be employed; and my fastening may be used for securing other articles or things than shutters, without departing from the spirit of my invention.

My improved fastening may be readily applied to the various descriptions of shutters now in use, irrespective of their thickness, and at a less cost than the ordinary means now employed for fastening them.

I am aware that a bolt, provided with one notch, has been used, in connection with a spring-catch, for securing shutters, but such a bolt can only be applied to the particular shutter for which it was intended, as the distance of the notch from the head must be exactly fixed to conform to the thickness of the sash and shutter, to allow the catch to engage therewith.

Claim.

What I claim as my invention, and desire to secure by Letters Patent, as a new article of manufacture, is—

The within-described fastening, consisting essentially of a bolt, *D*, provided with two or more notches and a weighted pawl, *H*, substantially as set forth.

WM. C. FISHER.
